RESILIENT SEAT CUSHION

Henry L. Burns, Yellow Springs, Ohio

Application February 20, 1946, Serial No. 649,106

4 Claims. (Cl. 155—179)

(Granted under the act of March 3, 1883, as amended April 30, 1928; 370 O. G. 757)

1

The invention described herein may be manufactured and used by or for the Government for governmental purposes without payment to me of any royalty thereon.

This invention relates to cushions generally and more particularly to fluid filled cushions intended to be used to support the human body in a sitting or reclining position. The invention has particular applicability for use in seat cushions for invalid chairs and for use aboard airplanes.

Presently known cushions do not adequately minimize body fatigue where the user of necessity is required to remain in one position over extended periods of time. Fatigue tests have indicated that seat cushions should be constructed to automatically conform to the anatomy of the user and at the same time should be adapted to supply varying supporting forces distributed over the supporting surface.

Accordingly, the principal object of this invention is the provision of a cushion that reduces fatigue to a minimum due to the fact that it is adapted to exert local supporting forces which correspond in magnitude to the applied load as such load is distributed over the cushion supporting surface.

A further object of the invention is the provision of a cushion comprising a plurality of interconnected fluid containing chambers which are of different sizes or are variously spaced apart, the one from the other, adapted to exert local supporting forces against the anatomy of the user and furnish pressure distribution in such a way as to result in maximum comfort to the user.

Another object of this invention is to provide a cushion which has its cushioning chambers spaced and its various parts arranged so as to furnish an adequate ventilating space between its chambers and parts in order to permit the cushion to be adequately ventilated and cooled under various conditions and during prolonged use, the structure being at the same time so arranged and braced as to obviate any danger of the cushioning chambers developing relative lateral movement the one to the other.

These and other objects of the invention will become apparent from the following detailed description taken in conjunction with the accompanying drawings in which:

Fig. 1 is a partly cut away perspective view of a cushion constructed in accordance with this invention;

Fig. 2 is a plan view of the cushion with certain upper elements removed to facilitate showing the arrangement of the resilient air filled chambers;

Fig. 3 is an enlarged cross-sectional view taken substantially on line 3—3 of Fig. 2.

As disclosed in the drawing, the cushion shown herein is made up of two sections secured together and comprising an upper set and a lower set of resilient chambers 2 and 2', respectively. The chambers are preferably made in the shape of bellows and are composed of rubber or similar material to retain air and render them resilient. These chambers 2 and 2' are secured to or are constructed integral with resilient sheets 3 and 3', and said sheets are secured fixedly together which further serves for laterally stabilizing the bellows assembly. Connecting channels 4 and 4' are formed integrally with said sheets 3 and 3' extending laterally of said sheets, and serve to form passages 5 providing communication between said chambers; while the joined ends between each upper chamber 2 and its companion lower chamber 2' are open to provide communication between said two companion chambers.

The resilient sheets 3 and 3' are secured together by cement, glue or other suitable material in such a way as to cause the resilient chambers 2 mounted on resilient sheet 3 to coincide in opposed relationship to resilient chambers 2' mounted on resilient sheet 3'. The resilient sheets 3 and 3' and connecting passages 4 are constructed of rubber like said chambers. Stem and valve means are suitably connected to the system of chambers to supply fluid, such as air, to the interiors of the chambers and connecting passages for inflating these chambers. While the fluid used may be either gaseous or liquid, valve means 6 as shown is more suitable for supplying gaseous fluid.

The ends of the resilient chambers remote from the resilient sheets 3 and 3' are caused to remain properly oriented by means of porous fabric sheets 7 and 7' to which the upper and the lower ends of said chambers are respectively affixed by cement, glue or other suitable means. Thin felt or sponge rubber pads 8 and 8' are positioned adjacent to the exterior surfaces of porous fabric sheets 7 and 7' to distribute the supporting pressure of the spaced chambers and prevent discomfort to the user occasioned by relatively high localized pressures near the outer ends of the resilient chambers. The above described construction is completely encased in a fabric cover 9.

It should be noted that in this disclosed form of construction, the upper and lower sets of chambers or bellows 2 and 2' have their adjoining ends formed integral with the rubber sheets 3 and 3'

which are also fixed together; while the outward or remote ends of said bellows are similarly secured to fabric sheets 8 and 8'. This arrangement assures the retention of the bellows in their properly spaced positions, and it prevents any relative lateral movement between the various bellows or any shifting of the bellows laterally of the sheets.

Fig. 2 discloses in plan view the assembly with elements 6, 7, 8, and 9 removed showing the upper resilient chambers 2 on upper sheet 3, and connecting passages 5. As illustrated in said Fig. 2, this disclosed form utilizes four different sizes of resilient chambers. These include chambers 11 of the smallest diameter, chambers 12 of the next larger diameter, chambers 13 of still larger diameter, and chambers 14 of the largest diameter, the arrangement of the four sizes of resilient chambers being also shown in this Fig. 2. The resilient chambers 14 of the largest diameter are grouped together and located midway between the sides of the cushion and slightly nearer to the rear; resilient chambers 11 of the smallest diameter occupy positions along the front edge of the cushion; and the resilient chambers 12 and 13 of intermediate sizes are variously positioned with respect to the largest and smallest resilient chambers.

Since the interiors of all the resilient chambers are interconnected, the fluid pressure at any given instant inside these chambers will be the same, and as a result the upward force exerted by a particular resilient chamber is proportional to the effective diameter and size of such chamber. The manner in which the different sizes of resilient chambers are arranged, as shown in Fig. 2, forms a construction pattern found to be most suitable in minimizing fatigue. This pattern is in accordance with the principle that the local supporting forces should be proportional to the corresponding local forces applied to the cushion due to the weight of the user.

It is not entirely necessary in utilizing my invention to use resilient chambers of different diameters. Resilient chambers of the same effective diameters could be used instead to accomplish the desired results by grouping such chambers close together where the applied local load will be relatively great and by spreading these chambers farther apart where the applied local load will be relatively light.

While I have described particular embodiments of my invention, it is to be understood that I do not wish to be restricted thereto and that I intend to cover all modifications thereof which would be apparent to one skilled in the art and which come within the spirit and scope of the appended claims.

I claim:

1. In a cushion construction a pair of juxtaposed resilient sheets secured together, fluid filled resilient bellows of different effective size and resisting force constructed integrally with each of said resilient sheets and positioned substantially directly laterally therefrom so that each bellows of one resilient sheet is in alignment with the corresponding bellows on the other sheet to form a plurality of resilient chambers, the chambers of an aligned pair being in communication, channel means formed on said sheets providing a plu-

rality of passages thereby connecting the interiors of said resilient chambers together, and means wherethrough to supply fluid to the interiors of said chambers and said passages.

5. 2. In a cushion construction, a pair of juxtaposed resilient sheets, fluid filled resilient bellows of different effective diameters constructed integrally with each of said resilient sheets and positioned substantially perpendicular thereto so that each bellows of one resilient sheet is aligned with the corresponding bellows on the other sheet to form a plurality of fluid filled resilient chambers, a plurality of passages connecting the interiors of said resilient chambers together, and means for supplying fluid to the interiors of said chambers and passages.

3. In a cushion construction, a plurality of fluid filled resilient chambers of different effective diameters, passages connecting the interiors of 20 all of said chambers, a pair of fabric sheets to which the outward ends of said resilient chambers are affixed, additional sheet means connected to all of said chambers, substantially midway between said fabric sheets, said pair of fabric 25 sheets together with said intermediate sheet means serving to retain the chambers against relative lateral movement, a pair of pads positioned adjacent the exterior surfaces of said fabric sheets, and a cover completely enclosing said 30 resilient chambers, fabric sheets, pads, and passages.

4. A resilient cushion construction comprising, a plurality of fluid filled chambers each having opposed substantially parallel circular ends and 35 a side wall formed by a revolution of corrugated resilient material about an axis passing centrally through said circular ends and each adapted to resiliently resist load in opposite directions along the axis thereof, said chambers all being oriented 40 in their load resisting directions, a yieldable fabric pad affixed to the opposite circular ends of said chambers for distributing a concentrated load over more than one of said chambers and for supporting said chambers in their oriented 45 direction, and passage means connecting the interior of all of said chambers with a fluid inlet, said passage means being formed in a sheet substantially midway between said yieldable pads and made integral with the side wall of all of 50 said chambers to retain the chambers against relative lateral movement.
